(57) **CLAIM**

The ornamental design for a fishing lure, as shown and described.

DESCRIPTION

FIG. 1 is a perspective view from the front of a first presently preferred embodiment of the fishing lure of the present invention;

FIG. 2 is a front view thereof;

FIG. 3 is a rear view thereof;

FIG. 4 is a top end view thereof;

FIG. 5 is a bottom end thereof;

FIG. 6 is a side view thereof from the right;

FIG. 7 is a side view thereof from the left;

FIG. 8 is a perspective view from the front of a second presently preferred embodiment of the fishing lure of the present invention;

FIG. 9 is a front view thereof;

FIG. 10 is a rear view thereof;

FIG. 11 is a top end view thereof;

FIG. 12 is a bottom end thereof;

FIG. 13 is a side view thereof from the right; and,

FIG. 14 is a side view thereof from the left.

The broken lines in the foregoing drawings are for illustrative purposes only and form no part of the claimed design.
